UNITED STATES PATENT OFFICE.

ENOCH GERARD WICKERSHAM, OF LEWISTON, MICHIGAN.

DIFFUSION-BATTERY.

SPECIFICATION forming part of Letters Patent No. 737,184, dated August 25, 1903.

Application filed May 27, 1903. Serial No. 158,985. (No model.)

To all whom it may concern:

Be it known that I, ENOCH GERARD WICKERSHAM, a citizen of the United States, residing at Lewiston, in the county of Montmorency and State of Michigan, have invented a new and useful Diffusion-Battery, of which the following is a specification.

My invention relates to improvements in a diffusion-battery for extracting the essential from crude drugs and sugar from saccharine material—such as beets, cane, &c.—in which the material is elevated through cells arranged on an incline and between rollers. Hot water being admitted to the upper cells overflows, 15 passing in the opposite direction downward through each cell.

The object of my improvement is to afford a simple and effective method of extracting the essential part from the material used.

20 I attain these objects by the mechanism illustrated in the accompanying drawings, in which—

Figure 1 is a view in perspective of the entire machine. Fig. 2 is a vertical section of 25 the entire machine.

Similar letters refer to similar parts throughout both views.

a is the body of the pan, being inclined lengthwise to the horizontal, the bottom having 30 a number of depressions forming cells *c c c*, the number of cells in a working machine being at least a dozen. The machine being inclined, hot water is admitted at *g* to the upper cell, which when filled overflows 35 into the next lower, thus filling each cell alternately, the hot water and juice flowing downward by gravitation through the beets, diffusing out the saccharine juice. When it overflows the lower cell, it falls into the tank *k* 40 and passes into the carbonation-tanks and filter-presses, which are not a part of this invention. In the bottom of the pan, running from the lowest to highest cell, is an elevator-belt *b*, carrying the sliced beets, being 45 deflected downward to the bottom of each cell by the rollers *d d d*, and rising between each cell is passed between the rollers *e f*, which remove a portion of the juice and water of diffusion, making the change a radical one 50 between each cell.

A drive-belt is run from a source of power over the pulley *l*, which by the aid of sprocket-wheels and the chain belt *m* communicates

motion to all the rollers and to the elevator-belt *b*. Beets are admitted from the grinder 55 through the shaft *h* into the lower cell and after passing through each cell and being thoroughly diffused are discharged into the chute *j*.

In this invention I do not confine myself to 60 a belt for an elevator, but contemplate the use of any other elevator which will force the sliced beets through the cells and accomplish the same end, which may be done by the rollers independently. 65

What I claim as my invention, and desire to secure by Letters Patent, is—

1. In an apparatus for diffusing drugs, salt and sugar, the combination comprising, a pan set at an angle to the horizontal having 70 a number of depressions forming cells, an elevator-belt adapted for carrying the substance being diffused through each cell, a roller in each cell adapted to submerge the substance being diffused to the bottom of this cell and 75 elevate the substance to the next higher cell, a pair of rollers between each cell through which the material is passed adapted for extracting a portion of the diffused juice, a pipe adapted to admit hot water or other 80 menstruum to the upper cell of the inclined series overflowing each cell in succession, a steam-jacket beneath the cells adapted to keep them hot, a series of belting connecting the rollers with a suitable power giving motion thereto, substantially as described and set forth.

2. In an apparatus for extracting sugar from saccharine vegetation the combination of an inclined pan having a series of depressions forming cells, heated by a steam-jacket to which water is admitted to the highest cell overflowing each cell in succession with an elevator adapted for carrying substance to be diffused beneath rollers to the bottom 90 of each cell elevating the same between rollers extracting a portion of the juice therefrom, substantially as described and set forth. 95

In testimony whereof I have signed my name to this specification in the presence of 100 two subscribing witnesses.

ENOCH GERARD WICKERSHAM.
